UNITED STATES PATENT OFFICE

152,234

DESIGN FOR A COMBINATION ASH TRAY AND DESK UNIT

George B. Wisecarver, Pikeville, Ky.

Application July 30, 1947, Serial No. 140,615

Term of patent 14 years

(Cl. D74—1)

To all whom it may concern:

Be it known that I, George B. Wisecarver, a citizen of the United States of America, residing at Pikeville, in the county of Pike and State of Kentucky, have invented a new, original, and ornamental Design for a Combination Ash Tray and Desk Unit, of which the following is a specification, reference being had to the accompanying drawing, forming a part thereof wherein:

Fig. 1 is a perspective view of a combination ash tray and desk unit, showing my new design.

Fig. 2 is a top plan view.

Fig. 3 is an end view, and

Fig. 4 is a section taken on line 4—4 of Fig. 2.

I claim:

The ornamental design for a combination ash tray and desk unit, as shown.

GEORGE B. WISECARVER.
